UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

LUMINOUS ELECTRIC HEATER.

Application filed April 18, 1918. Serial No. 229,433.

To all whom it may concern:
Be it known that we, FRANK KUHN and JAY A. HAND, both citizens of the United States of America, residing at Detroit, in the county of Wayne and State of Michigan, have invented certain new and useful Improvements in Luminous Electric Heaters, of which the following is a specification, reference being had therein to the accompanying drawings.

This invention relates to luminous electric heaters and particularly relates to electric heaters of the type employing a heating unit located substantially at the focus of a concave reflector so as to concentrate the radiation of heat substantially in one direction.

It is the object of the invention to increase the efficiency of electric heaters of this type by the provision of a heating unit that will offer a minimum obstruction to the waves or rays reflected from the concave surface; which will approximate as closely as possible the effect of heat radiating from the focal point of the reflector and which will throw the heat rays or waves uniformly upon the reflecting surface at all sides of the unit.

In the accompanying drawings:
Figure 1 is a front view of the heater;
Figure 2 is a view of the same in side elevation and partial section.

In these views the reference character 1 designates a concave reflector, preferably ellipsoidal, and 2 a resistor-coil upon a hollow insulatory core 3, said core and coil being co-axial with the reflector and being substantially symmetrical with respect to the focus thereof. The diameter of said core and of the coil wound thereupon increases gradually from the extremities of the unit to its center, as is clearly seen in Figure 2. The rear end of said core is engaged within a tubular holder 4 passing through the reflector and embraced by an annular flange 5 rearwardly projecting from the reflector, said holder and the heating unit carried thereby being axially adjustable in said embracing flange to properly adjust the unit with respect to the focus. The rear portion of the holder 4 is filled with insulatory material 6 in which a pair of terminals 7 are imbedded, said terminals projecting rearwardly beyond the holder. The reflector is

formed at its periphery with a return-bent flange 8, which flange is embraced by a ring 9 flanged inwardly at its rear edge, as indicated at 10, the flange 10 engaging behind the flange 8 to restrain said ring against forward removal from the reflector. Said ring is formed with a series of spaced hooks 11 which peripherally engage a wire guard 12 of concave shape, said guard preferably having the shape of a rosette, as is shown by Figure 1.

Since the convolutions of the coiled resistor 2 are co-axial with the reflector, the heat radiated from said resistor will impinge upon the reflecting surface substantially uniformly at all sides of the heating unit. The co-axial relation of said unit with the reflector is further advantageous, in that it minimizes the obstruction offered thereby to the reflected radiation of heat. The tapering of the unit from its center to its ends is advantageous, in that the convolutions at the inner end portion of the unit do not obstruct radiation from the convolutions adjacent the center of the unit and similarly the convolutions adjacent the outer end of the unit offer no obstruction to radiation from the convolutions of greater diameter.

By the use of an ellipsoidal reflector, the reflected rays are given a substantially conical form, the apex of the core of rays being the focus conjugate to that at which the heating unit is mounted. By varying the differential relation between the major and minor axes of the ellipse transcribing the ellipsoidal surface, the distance of the apex of the cone of rays from the reflector may be varied without change in the maximum diameter of the reflector. While theoretically the rays from a concave surface must emanate from the focus thereof in order to be reflected uniformly in a predetermined direction, it has been found that an ellipsoidal reflector will collect heat rays originating anywhere close adjacent to its focus and converge them as indicated in dotted lines in Figure 2.

It has been found that with the same resistor a much greater heat radiation is secured when the same is coiled as above described instead of being given the ordinary cylindrical shape.

What we claim as our invention, is:
1. In a luminous electric heater, the com-

bination with a concave reflector, of a guard therefor arched across the front of said reflector, an annular member peripherally mounted upon the reflector, and a series of 5 hooks carried by said annular member to which said guard is detachably engaged.

2. In a luminous electric heater, the combination with a concave reflector, of a ring encircling the reflector at the front thereof, 10 and a guard arched over the front of the reflector detachably engaged with said ring at a plurality of points.

3. In a luminous electric heater, the combination with a concave reflector formed 15 with a return-bent annular flange at its periphery, of a ring embracing the return-bent flange of the reflector and restrained thereby against forward displacement, and a guard arched over the front of the reflector and 20 peripherally attached to said ring.

4. In a luminous heater, the combination with an ellipsoidal reflector, of a heating unit located substantially at the focus of said reflector and coaxial therewith, said 25 unit having a diameter gradually increasing from its extremities to an intermediate point thereof.

5. In a luminous heater, the combination with a concave reflector, of an electrical 30 heating unit comprising a core of gradually varying diameter and a resistor wound on said core, said unit being mounted with its axis substantially coinciding with the central axis of the reflector.

6. In a luminous heater, the combination 35 with a concave reflector, of an electrical heating unit comprising a core member having its diameter gradually decreased from its center to its extremities and a resistor 40 wound upon said core member, said unit being mounted with its longitudinal axis substantially coinciding with the central axis of the reflector, whereby the heat rays will be reflected in substantial parallelism.

7. In a luminous heater, the combination 45 with a concave reflector, of an electrical heating unit comprising a coil resistor having its convolutions successively varied in diameter and a mounting for said resistor, said unit being mounted with the axis of 50 said resistor substantially coinciding with the central axis of the reflector.

8. In an electric heating unit adapted for use in conjunction with a concave reflector, 55 an insulating core member having its diameter gradually decreased from its center to its ends, and a resistor wound upon said core member, said unit being adapted for mounting with its longitudinal axis coincident with the central axis of the reflector, 60 whereby the heat rays will be reflected in substantial parallelism.

9. In an electric heating unit adapted for use in conjunction with a concave reflector, 65 a resistor forming a coil and having the diameter of its convolutions gradually decreased from the center to the extremities of said coil, and a mounting for said resistor with its longitudinal axis coincident with the central axis of the reflector, whereby the 70 radiation from said resistor convolutions will be uniformly distributed over the surface of said reflector, and the reflected rays arranged in substantial parallelism.

10. In an electric heating unit adapted for 75 use in conjunction with a concave reflector, a spirally grooved insulating core having its diameter gradually decreasing from its center portion to its extremities, and a resistor 80 wound upon said core in said groove and formed of coiled wire, said unit being adapted for mounting with its axis coincident with the center axis of the reflector, for the purpose described.

In testimony whereof we affix our signatures. 85

FRANK KUHN.
